UNITED STATES PATENT OFFICE.

JAMES H. DIAMOND, OF ALLEGHENY, PENNSYLVANIA.

DESIGN FOR A FACE-BOARD FOR GAS-BURNERS.

SPECIFICATION forming part of Design No. 30,545, dated April 11, 1899.

Application filed December 21, 1897. Serial No. 662,939. Term of patent 7 years.

To all whom it may concern:

Be it known that I, JAMES H. DIAMOND, a citizen of the United States, residing at Allegheny, in the county of Allegheny and State 5 of Pennsylvania, have invented and produced a new and original Design for a Face-Board for Gas-Burners, of which the following is a specification, reference being had to the accompanying drawings, forming part hereof, 10 in which—

Figure 1 indicates a plan view of a face board or plate for gas-burners made in accordance with my design. Fig. 2 is a vertical section on line A B of Fig. 1.

15 A is an upright plate or board constituting the face of a gas-burner, said board having

a series of diamond-shaped blocks B B, formed by the series of diagonally-arranged perforations a b, the perforations of each series being parallel and intersecting the other series, 20 as shown, the said diamond-shaped blocks having a rough or shaggy appearance.

What I claim is—

The design for a face board or plate for gas-burners, as herein shown and described. 25

In testimony whereof I have hereunto affixed my signature in the presence of two witnesses.

JAMES H. DIAMOND.

In presence of—

A. K. STEVENSON,
C. E. WILLIAMS.
